UNITED STATES PATENT OFFICE

149,282

DESIGN FOR A BOOK END

Alexander Leva, New York, N. Y.

Application November 20, 1946, Serial No. 134,950

Term of patent 3½ years

(Cl. D33—1)

To all whom it may concern:

Be it known that I, Alexander Leva, a citizen of the United States of America, residing in New York city, county of Queens, and State of New York, have invented a new, original, and ornamental Design for a Book End, of which the following is a specification, reference being had to the accompanying drawing, forming part thereof.

Fig. 1 is a front perspective view of a book end, showing my new design.

Fig. 2 is a rear perspective view.

I claim:

The ornamental design for a book end, substantially as shown.

ALEXANDER LEVA.
